Primary Examiner — Ricky Pham(74) *Attorney, Agent, or Firm* — Bachman & LaPointe, P.C.(57) **CLAIM**

The ornamental design for a folding dehydrator, as shown and described.

DESCRIPTION

FIG. 1 is a top side perspective view of a folding dehydrator showing our new design thereof;

FIG. 2 is a rear view of the folding dehydrator of FIG. 1;

FIG. 3 is a front view of the folding dehydrator of FIG. 1; FIG. 4 is a right side view of the folding dehydrator of FIG. 1;

FIG. 5 is a left side view of the folding dehydrator of FIG. 1;

FIG. 6 is a top view of the folding dehydrator of FIG. 1; and, FIG. 7 is a bottom view of the folding dehydrator of FIG. 1. The broken lines shown in the drawings are for illustrative purposes only and form no part of the claimed design.
